UNITED STATES PATENT OFFICE

2,422,449

FREQUENCY MODULATED TRANSMITTER

George L. Usselman, Port Jefferson, N. Y., assignor to Radio Corporation of America, a corporation of Delaware

Original application October 30, 1940, Serial No. 363,447, now Patent No. 2,297,926, dated October 6, 1942. Divided and this application September 1, 1942, Serial No. 456,859

10 Claims. (Cl. 179—171.5)

1

The present invention relates to frequency modulators and, more particularly, to a frequency modulator using the multi-vibrator principle.

This application is a division of my United States application Serial No. 363,447, filed October 30, 1940, now United States Patent No. 2,297,926, dated October 6, 1942.

Most prior art frequency modulators use reactance tubes to vary the effective reactance of an oscillator circuit to obtain frequency modulation. This usually requires one or more extra tubes. In the present invention, in the preferred circuits, I apply the audio modulating potentials directly to the multi-vibrator tubes; that is, to the tubes which produce the oscillations and wherein modulation takes place. In my arrangement, a pair of tubes connected in reactive and resistive circuits of the multi-vibrator type are used and the resistance in the circuits is varied at signal frequency to vary the frequency of operation of the multi-vibrator circuit.

In a modification, means is included for balancing amplitude variations produced by change of potential on one tube electrode by opposite and equal variations of the potential on another tube electrode to thereby produce substantially frequency modulation only of the oscillations generated with little or no amplitude modulation.

In describing my invention, reference will be made to the attached drawings wherein:

Figs. 1 to 4, inclusive, each shows a frequency modulator comprising a pair of multi-vibrator tubes with means for modulating elements in the multi-vibrator circuits to thereby modulate the frequency at which they operate.

In Fig. 1, an external grid circuit resistance of the tubes is modulated, this being one of the elements which determines the time constant of the multi-vibrator circuits and, consequently, the frequency of operation thereof.

In Fig. 2, a resistance in the plate circuit of each tube in the multi-vibrator circuits is varied.

In Fig. 3, the screen grid potentials are modulated to thereby modulate the tube impedance and means is provided for stabilizing the mean frequency of operation of the multi-vibrator.

In Fig. 4, the screen grid potentials are modulated, and means is provided for balancing out any amplitude modulation produced.

The modulators of all of the systems may feed the frequency modulated wave energy to the necessary and well known amplifying, amplitude limiting and frequency multiplying circuits, some of which have been illustrated.

In Fig. 1, two tubes V1 and V2 have their anodes and grids cross-connected by condensers C1 and C2. That is, the anode 6 of tube V1 is connected by condenser C2 to the grid 8 of tube 60

2

V2, while the anode 10 of tube V2 is connected by condenser C1 to the grid 12 of tube V1. The grid 12 of tube V1 is connected to its cathode 11 by a resistance R1, while the grid 8 of tube V2 is connected to its cathode 13 by a resistance R2. The anodes 6 and 10 are connected by resistors 14 and 18 and the primary winding of a transformer 20. A source of potential 17 is connected between a point on the primary winding of transformer 20 and the cathodes 11 and 13 to supply plate potential to anodes 6 and 10. The secondary winding of this transformer 20 supplies the output of the modulated multi-vibrator to a pair of amplifier tubes V5 and V6.

15 The condensers C1 and C2 and resistances 14, 18, R1 and R2 form the time constants of the circuit which determines the frequency of operation thereof. The condensers C1 and C2 are charged, discharged and recharged at a rate determined by their size and the size of resistances 14, 18, R1 and R2. During each impulse the condensers C1 and C2 are discharged and charged in reverse sense at a high frequency.

In a multi-vibrator circuit the condenser

25 charging circuit consists of the condenser, the grid resistor and the opposite tube anode resistor. Anything that affects the current in this circuit will affect the condenser charging rate. That is, if the value of condenser or any resistor is

30 changed, the charging rate and the oscillator frequency will be changed. If the potentials are changed in such a way as to change the charging current, the charging rate and frequency of operation will be changed. If the tube resistances

35 are changed by applying modulating potentials to some of the tube elements, that will change the charging rate of the condensers by changing the voltage drop in the anode resistor due to the change in tube current. In other words, if the anode potential is considered as the source of current passing through the condenser C1 or C2 and through the grid leak resistor R1 or R2 to ground, then it can be seen that a change in the

40 anode potential, such as would occur during modulation of the tube current, changes the charging rate of the condensers and thereby changes the oscillator frequency.

Another way to look at it is to consider that 50 the condenser C1 or C2 and grid leak resistor R1 or R2 are connected in parallel to the opposite tube anode to cathode tube resistance. This combination is connected in series with the tube anode supply resistance. This latter resistance 55 serves to limit the total current so that when the tube current increases, the condenser current decreases and vice versa. When a higher condenser discharge rate exists, then a higher frequency of push-pull oscillations exists in the multi-vibrator circuit. The operation of a multi-

vibrator circuit is well known to the art. It is a sort of self regenerating tripping circuit.

Since the frequency of operation depends in part on the resistances R_1 and R_2 , modulation of said resistances at signal frequency will correspondingly modulate the frequency of oscillation of the multi-vibrator. I modulate the resistances R_1 and R_2 by means of a modulation amplifier 30 having its cathode grounded and having a pair of anodes 32 and 34 connected to points on R_1 and R_2 , respectively. The anodes 32 and 34 of tube 30 may derive their potentials from resistors R_1 and R_2 and their currents from the grid circuits of tubes V_1 and V_2 as shown, or the cathode of tube 30 may be connected to the negative terminal of a source shunted by an audio frequency bypass condenser, the negative terminal of which is grounded. The control grid 36 of tube 30 is connected to a source of modulating potentials 37 by way of transformer 38. The source of modulating potentials may represent voice signals, television signals, video signals, etc.

The frequency modulated oscillations are supplied to the grids 40 and 42 of amplifiers V_5 and V_6 for amplification therein. The anodes of tubes V_5 and V_6 supply the amplified modulated oscillations to a transformer 44 and from the transformer 44 by way of a filter 50 to a frequency multiplier and amplifier and limiter 60.

In Fig. 2, I also illustrate a frequency modulator circuit using a multi-vibrator oscillator. In this circuit the modulation is applied to the anodes 6 and 10 of the oscillator tubes V_1 and V_2 through resistors R_3 and R_4 and R_5 and R_6 . Modulation of tubes 30 and 30' in effect varies the resistance in the anode circuit of the multi-vibrator, thereby varying the frequency. The output is passed through amplifiers and filters also before it reaches the load.

In Fig. 3, I modulate the screen grids 3 and 5 in phase by modulating potentials from the source 37. Changing the screen grid potential changes the resistance or impedance of the tubes V_1 and V_2 . These tube resistances are part of the time constant circuits and, consequently, partly control the frequency of operation thereof. Thus, the frequency variations correspond to the amplitudes of the modulating potentials. In Fig. 3 the output circuit comprising inductance of the primary of transformer 20, condenser C_3 and resistances R_5 and R_6 is a broadly tuned resonant circuit, the purpose of which is to introduce some degree of frequency stability to thereby hold the oscillator at an approximately fixed mean frequency, to improve the output wave shape of the modulator and yet to permit wide band frequency modulation to be accomplished.

In Fig. 4 the modulating circuits are arranged in such a way as to balance out amplitude modulation.

Now, as a rule, the current and voltage wave shape of a multi-vibrator is not like a sine wave and the frequency stability is poor because it changes with power voltage variations. In the circuit of Fig. 4 it may be noted that the cathodes 11 and 13, control grids 12 and 14 and the screen grid electrodes 3 and 15 of tubes V_1 and V_2 are used for the multi-vibrator oscillator circuit of the modulator, while the anodes of tubes V_1 and V_2 are used in the output circuit of the modulator. The anodes 6 and 10 of tubes V_1 and V_2 are connected in push-pull relation to tuned circuit L_1 , C_3 . The center point of inductance L_1 is connected by R_7 to power source

17. The inductance L_1 and the variable condenser C_3 form a tank circuit which is tuned to the carrier frequency. Of course, condensers C_1 , C_2 and resistors R_1 , R_2 , R_3 , R_4 must also have the correct values to operate at the carrier frequency. The tank circuit L_1 , C_3 acts both as a frequency stabilizer and as a filter to give a substantially sine wave shape output. In other words, the sine wave current oscillations in tank circuit L_1 , C_3 are maintained by and guided by the multi-vibrator current oscillations which are not sine wave shape. To obtain correct operation the proper ratio of voltages supplied from source 17 must be maintained between the anodes 6 and 10 and the screen grids 3 and 5. Too much control by the oscillator screen grid circuit will result in poor wave shape output. Too much control by the anode circuit will cause reduction of modulator band width.

20. The signal modulating potentials are applied in phase to the screen grids 3 and 5 of tubes V_1 and V_2 of the multi-vibrator oscillator circuit of the modulator to produce the frequency changes. The signal modulating potentials from source 37 are applied to audio transformer 38. One terminal of the secondary winding of transformer 38 is connected to the screen grids 3 and 5 of tubes V_1 and V_2 through resistors R_3 and R_4 . The other terminal of transformer 38 is connected to the anodes 6 and 10 of tubes V_1 and V_2 through resistor R_7 and through coil L_1 . The power source 17 is connected between the cathodes 11 and 13 of tubes V_1 and V_2 , and some suitable point on the secondary winding L_1 of transformer 38.

30. During the modulating cycle, take an instance when the screen grid potential is made more positive. This causes a change in the modulator frequency but it would also cause more current to reach the anodes of tubes V_1 and V_2 . However, the fact that power source 17 is tapped somewhere between the output terminals of transformer 38 means that when the screen grid potentials are modulated in the positive direction, the anodes of tubes V_1 and V_2 are modulated in a negative direction and vice versa. Now if the tapped position of power source 17 on the secondary winding of transformer 38 is properly chosen, the amplitude modulation is balanced out so that only frequency modulated carrier reaches the antenna. The variable resistor R_1 is placed in series with the anode circuit of tubes V_1 and V_2 in order that the average ratio of power delivered to the screen grid circuit and the anode circuit of the frequency modulator, may be properly adjusted. This is essential for proper operation of the modulator. The arrangement of Fig. 4 does not require a limiter stage for limiting out the amplitude modulation.

60. 55. 50. 45. 40. 35. 30. 25. 20. 15. 10. 5. 4. 3. 2. 1. 0. What is claimed is:

1. In a frequency modulator, an electron discharge device having an anode, a cathode, a control grid and a screen grid, circuits including capacity and resistance interconnecting the screen grid, control grid, and cathode of said device to form a multi-vibrator oscillator, a source of direct-current potential connecting the anode and screen grid of said device to the cathode of said device, connections for modulating the potentials on the screen grid and anode of said device in accordance with signals to thereby modulate a constant of said multi-vibrator oscillator and correspondingly vary the frequency of operation thereof, and an output circuit connected to the anode of said device.

2. In a wave length modulator, a generator of wave energy to be modulated including a pair of electron discharge tubes each having electrodes including a cathode, a control grid, a screen grid, and an anode, a condenser coupling the control grid of one tube to the screen grid of the other tube, a condenser coupling the control grid of the other tube to the screen grid of said one tube, a source of direct current potential, a resistance coupling the screen grids of each of said tubes to a point of positive potential on said source, a resistance coupling the control grid of each of said tubes to the cathodes of said tubes, a connection tying the cathodes of said tubes together and to a point on said source of direct current potential, an output circuit coupling the anodes of said tubes in push-pull relation, and a source of modulating potentials coupled to the anodes and to the screen grids for modulating the potentials thereon.

3. In a frequency modulation system, a pair of electron discharge devices each having a heated cathode and cold electrodes including an electrode serving as an anode, and a control grid, capacities interconnecting the electrode serving as an anode of each of said devices with the control grid of the other of said devices, resistances connected between electrodes of each of said devices, means for applying direct-current potentials to the electrodes of said devices, an output circuit coupled in push-pull relation with corresponding cold electrodes of said devices, a modulator tube having a control grid, a cathode and two anodes, connections for applying modulating potentials to the control grid and cathode of said modulator tube, and couplings between the two anodes of said modulator tube and corresponding electrodes of said devices.

4. In a frequency modulation system, a pair of electron discharge devices each having electrodes including a screen grid, an anode, a cathode, and a control grid, capacities cross-connecting corresponding electrodes of said devices, resistances connected between the cathodes and control grids of said devices, a source of direct current potential connected to the cathodes of said devices, resistance connecting the anodes of said devices to said source of direct current potential for applying direct current potentials to the said anode electrodes of said devices, an output circuit coupled in push-pull relation with the anode electrodes of said devices, a transformer having a primary winding excited by modulating potentials and having a secondary winding, a coupling between a point on said secondary winding and the cathodes of said devices, a coupling between one end of said secondary winding and the screen grids of said devices, and a coupling between the other end of said secondary winding and the anodes of said devices.

5. In a frequency modulation system, a multi-vibrator including a pair of electron discharge devices each having electrodes including an anode, a cathode and a control grid, a capacitor connecting the control grid of each device to an electrode of the other device serving as an anode in said multi-vibrator, a source of direct current potential having a negative terminal connected to the cathodes of said devices, a resistor connecting each of the electrodes serving as anodes of said multi-vibrator to a positive terminal of said source of direct current potential for applying positive direct current potentials to the said electrodes of said devices serving as anodes, a resistor connecting the control grid of each of

said devices to the cathodes of said devices, an output circuit including an inductor coupled in push-pull relation with the anodes of said devices, the arrangement being such that oscillations are generated in said devices and circuits of a frequency depending in part on the circuit impedance, and connections to corresponding cold electrodes of said devices for varying the potential thereon in synchronism in accordance with signals to correspondingly vary the circuit impedance and the frequency of the oscillations generated.

6. A system as recited in claim 5 wherein said corresponding cold electrodes modulated in synchronism are the control grids of said devices.

7. In a frequency modulation system, a multi-vibrator including a pair of electron discharge devices each having electrodes including an anode, a cathode, a screen grid and a control grid, a capacitor connecting the control grid of each device to an electrode of the other device serving as an anode in said multi-vibrator, a source of direct current potential having a negative terminal connected to the cathodes of said devices, a resistor connecting each of the electrodes serving as anodes of said multi-vibrator to a positive terminal of said source of direct current potential for applying positive direct current potentials to the said electrodes serving as anodes, a resistor connecting the control grid of each of said devices to the cathodes of said devices, an output circuit coupled with the anode electrodes of said devices, the arrangement being such that oscillations are generated in said devices and circuits of a frequency depending in part on the circuit impedance, connections to corresponding cold electrodes of said devices for varying the potentials thereon in accordance with signals to correspondingly vary the circuit impedance and the frequency of the oscillation generated and reactance in said output circuit tuned to the frequency of the oscillations generated to stabilize the same and to provide output oscillations of substantially sine wave form.

8. A system as recited in claim 7 wherein said reactance includes an inductor and capacitor in parallel connecting the output electrodes in push-pull relation.

9. In a frequency modulation system, a multi-vibrator including a pair of electron discharge devices each having electrodes including an anode, a cathode, a screen grid and a control grid, a capacitor interconnecting the control grid of each device to the anode of the other device, a source of direct current potential having a negative terminal connected to the cathodes of said devices, a resistor connecting the anode of each device to a positive terminal of said source of direct current potential for applying positive di-

rect current potentials to the anodes, a resistor connecting the control grid of each of said devices to the cathodes of said devices, an output circuit coupled in push-pull relation with the anodes of said devices, the arrangement being such that oscillations are generated in said devices and circuits of a frequency depending in part on the circuit impedance, connections to the screen grids of said devices for varying the potential thereon in phase in accordance with signals to correspondingly vary the circuit impedance and the frequency of the oscillation generated, and an inductor and capacitor in parallel in said output circuit tuned to the frequency of the oscillations generated to stabilize the same

to provide output oscillations of substantially sine wave form.

10. In a frequency modulation system, a multivibrator including a pair of electron discharge devices each having electrodes including an anode, a cathode, a screen grid and a control grid, a capacitor connecting the control grid of each device to the screen grid of the other device, a source of direct current potential having a negative terminal connected to the cathodes of said devices, a resistor connecting the screen grid of each device to a positive terminal of said source of direct current potential for applying positive direct current potentials to the said screen grids of said devices, a resistor connecting the control grid of each of said devices to the cathodes of said devices, an output circuit coupled in push-pull relation with anodes of said devices, the arrangement being such that oscillations are generated in said devices and circuits of a frequency depending in part on the circuit impedance, connections to the screen grids of said devices for varying the potential thereon in phase in accord-
